UNITED STATES PATENT OFFICE.

JAMES M. RUDE, OF COVINGTON, KENTUCKY.

RECEPTACLE-CLEANSING APPARATUS.

1,308,195.

Specification of Letters Patent.

Patented July 1, 1919.

Application filed March 4, 1918. Serial No. 220,211.

To all whom it may concern:

Be it known that I, JAMES M. RUDE, a citizen of the United States, residing at Covington, in the county of Kenton and State of Kentucky, have invented certain new and useful Improvements in Receptacle-Cleansing Apparatus; and I do hereby declare the following to be a full, clear, and exact description of the invention, such as will enable others skilled in the art to which it pertains to make and use the same.

This invention relates to improvements in the art of the reclamation of containers and receptacles such as have heretofore customarily been discarded after a single use, the invention being directed to mechanism for the cleansing of such containers.

The object in view is the production of relatively inexpensive and simple means for effectively cleansing such a container as a used tin can or other receptacle.

To this end, the invention comprises revolving brushes and means for moving the brushes for varying the diameter of the circles described by the peripheral portions thereof.

The invention comprises certain other novel constructions, combinations and arrangements of parts as will in part herein-30 after become apparent and in part be stated.

In the accompanying drawings,—

Figure 1 is a view in side elevation of an apparatus embodying the features of the present invention.

Fig. 2 is a longitudinal, central vertical section through a portion of the machine seen in Fig. 1.

Fig. 3 is a transverse section therethrough taken on the plane indicated by line 3—3 of Fig. 2, and looking in the direction indicated by the arrows.

Fig. 4 is an end view thereof.

Figs. 5 and 6 are, respectively, transverse sections taken on the planes indicated by lines 5—5 and 6—6 of Fig. 2, and looking in the direction indicated by the arrows.

Fig. 7 is an end view of the tapering core with the brush segments and springs omitted.

Fig. 8 is an enlarged, detail, perspective view of one of the brushes detached.

Fig. 9 is a detail elevation of one of the terminal bristle-carrying segments with the bristles omitted.

Fig. 10 is a fragmentary section there-

through taken on the plane indicated by line 10—10 of Fig. 9.

Referring to the drawing by numerals, 1, 1 indicate the standards or other appropriate supports for bearings 2, 2 in which is journaled the tubular shaft 3 having the driving pulley 4 engaged by the belt 5. Any appropriate driving mechanism for rotating the shaft 3 may be employed. A cleansing fluid supply pipe 6 is supported at 7 and provided with a control valve 8. The pipe 6 extends axially into the tubular shaft 3, and terminates near one end thereof. The shaft 3 is provided at one end with a removable cap 9 having a central aperture 10 for the passage of cleansing fluid from the pipe 6. The discharge end of the pipe 6 is arranged adjacent the aperture 10 and a collar 11 surrounds the pipe and extends to the surrounding walls of the shaft 3 for preventing discharge of cleansing fluid otherwise than through the opening 10. A tubular tapered body 12 is detachably fixed to and outstands axially from the cap 9, the said body 12 being a truncated cone and, for convenience of reference, will hereinafter be called a conical body. Also, for convenience of reference, the end of the conical body 12 remote from the shaft 3 will be referred to as the outer end and the relative location of the other parts will be correspondingly indicated.

The conical body 12 is made up of four spaced segments, as clearly indicated in Fig. 3, and the said segments are connected at the outer end by a plate 13 which is fixed to the segments by screws, or in any other appropriate manner. The inner ends of the segments are connected together by virtue of their engagement with the cap 9, such engagement being effected by screws 14 extending through the cap and into the respective segments of the conical body. The said conical body is preferably made of metal, but may be constructed of other material when found desirable. The space between the several segmental members of the conical body 12 forms radial slots 15, 15, communicating with the tubular interior of the body. Mounted on each of the segments of the core 12 is a segmental brush consisting, as seen in detail in Fig. 8, of a plate 16, which is transversely arcuate and longitudinally tapered, corresponding in taper conversely to the taper of the core 12, whereby the exterior surface of the four segmental

plates 16, taken together, is substantially cylindrical. Fixed to each plate 16 is a bristle-carrying plate 17 having bristles 18 outstanding therefrom and forming substantially a complete cylinder. Each of the plates 17 is transversely arcuate, so that each plate 16 with its plate 17 forms a segment outstanding from the engaged segment of the core 12 and the plates 16 and 17 are proportioned to leave spaces between their edges continuing the radial slots 15 for permitting the discharge of cleansing fluid from the bore of the core 12 out to the bristles of the surrounding brush. The plates 16 with their brushes are movable longitudinally of the core 12, and to prevent angular shifting of the brushes each plate 16 is provided with an undercut groove 19 which interlocks with a correspondingly shaped key or tongue 20 outstanding along the respective engaged segment of the core 12. Each plate 17 is detachably fixed to its respective plate 16 by screws 21, 21, or other appropriate connecting means. One of the screws 21 for each plate 17 has an extended end portion 22 projecting through and beyond the plate 16 in the length of the groove 19 so as to extend into a cut-away portion 23 formed in the key or tongue 20. Thus the extent of longitudinal movement of the brush segments on the core segments is limited to the length of the cut-away portion 23.

Anchored in the cap 9, as by being tightly seated in sockets thereof, are springs 24, 24, preferably of the coiled type, one of said springs being provided for each of the brush segments and being located to engage the respective segments so as to press the same longitudinally outward. The brush which surrounds core 12 is thus held normally at the limit of its outward movement, and since the undercut tongue and groove connections between the brush segments and the core segments cause the brush segments to approach each other, or, in other words, contract as they move outward along the core, the brush proper, that is, the bristles, assumes the form of a smaller cylinder when in the position indicated in Fig. 2 than when the brush segments are moved inward along the core, such inward movement causing a proportional outward movement of the brush segments and a resulting expansion in the cylinder represented by the bristles.

To the outer end of each plate 16 is detachably fixed a terminal brush segment 25 having bristles outstanding substantially parallel to the axis of the cylindrical brush represented by the bristles of the first-mentioned brush segments. To each of the segmental plates 25 is fixed preferably a strip of rubber 26. This strip may be secured in any of various ways, one form of connection being seen in Figs. 9 and 10, wherein the rubber is cemented in an undercut groove 27

formed in the segment 25. The four segments 25 complete substantially a disk and the strips 26 form substantially a circle presenting a buffer or engaging element to be struck by the bottom of the receptacle to be cleansed, as hereinafter set forth. The segments 25 have their edges spaced apart to correspond with the slots 15 so as to allow the delivery of cleansing fluid to the terminal brushes and to the end of the receptacle 75 being cleansed.

In operation, a can or other receptacle to be cleansed is applied onto the brush by a longitudinal movement with the open end of the can advanced until the terminal 80 brush strikes the inner surface of the end of the can. Of course, any given machine is adapted for cleansing cans or other receptacles of varying sizes, but only such variations in size can be allowed as are within 85 the limits of effective operation of the particular machine. A can applied to the brush must be capable of ready application thereto while the brush is in its contracted condition. When the bottom of the can strikes 90 the rubber 26, further movement of the can causes the brush segments to travel inward along the core 12 and effects a proportional expansion of the brush which causes the bristles to engage the interior surface of 95 the can with the requisite force for effectively cleansing the same. When the can has been caused to assume this position, and while being held in this position, the power is turned on through the belt 5, or other 100 power mechanism, not shown, the cleansing fluid is turned on by the opening of the valve 8 and the can is held stationary for a sufficient length of time to be thoroughly cleansed and polished on its interior. The 105 rotation of shaft 3 is then discontinued and the can removed. The can may be applied onto the brush manually or by machinery as may be found preferable in any particular instance.

What I claim is:—

1. In receptacle cleansing apparatus, the combination with a rotary support, of a tubular conical core outstanding therefrom, and a brush slidably engaging the core to 115 slide longitudinally thereof while revolving therewith.

2. In receptacle cleansing apparatus, the combination with a rotary support, of a tubular conical core outstanding therefrom, 120 and a brush slidably engaging the core to revolve therewith, the brush being adapted to be moved along the core by pressure exerted by the receptacle being cleansed, and a spring engaging the brush and pressing 125 the same in a direction opposite to the line of pressure exerted by such receptacle.

3. In receptacle cleansing apparatus, the combination with a rotary support, of a tubular conical core outstanding therefrom, a 130

- brush slidingly engaging the core to revolve therewith, the brush being adapted to be moved along the core by pressure exerted by the receptacle being cleansed, a spring 5 engaging the brush and pressing the same in a direction opposite to the line of pressure exerted by such receptacle, and means for limiting the movement of the brush under the action of the spring.
- 10 4. In receptacle cleansing apparatus, the combination with a rotary support, of a tubular conical core outstanding therefrom, a brush slidingly engaging the core to revolve therewith, the brush being adapted to be moved along the core by pressure exerted by the receptacle being cleansed, a spring 15 engaging the brush and pressing the same in a direction opposite to the line of pressure exerted by such receptacle, and means extending from the brush into line with a portion of the core for limiting the movement of the brush under the pressure of the spring.
- 5 In receptacle cleansing apparatus, the combination with a revolvably mounted support, of a tapering plate connected thereto and outstanding axially therefrom to revolve therewith, and a brush engaging the plate to revolve therewith, the brush having a body tapering conversely to the taper of 30 the plate and the brush being mounted to move longitudinally of the plate for enabling the brush when so moved to be shifted radially relative to the axis of rotation.
6. In receptacle cleansing apparatus, the combination with a revolvably mounted support, of a tapering plate connected thereto and outstanding axially therefrom to revolve therewith, and a brush engaging the plate to revolve therewith, the brush having 35 a body tapering conversely to the taper of the plate and the brush being mounted to move longitudinally of the plate for enabling the brush when so moved to be shifted radially relative to the axis of rotation, the 40 plate and brush being formed with undercut tongue and groove connections extending longitudinally of the plate.
7. In receptacle cleansing apparatus, the combination with a revolvably mounted support, of a plate tapering along its exterior and connected to the support to revolve therewith and outstanding axially therefrom, and a brush engaging the plate to revolve therewith, the brush having a body 45 tapering conversely to the taper of the plate and the brush being mounted to move longitudinally of the plate for enabling the brush when so moved to be shifted outwardly radially relative to the axis of rotation.
8. In receptacle cleansing apparatus, the combination with a revolvably mounted support, of a tapering plate fixed to and outstanding axially from the support, and a conversely tapering brush slidingly mounted 60 on the plate, the brush and plate having undercut tongue and groove connections extending longitudinally thereof for causing the brush to revolve with the plate while enabling the brush to be slid along the plate, the plate being formed with a longitudinal 70 recess and a pin removably connected with the brush and extending into the recess for limiting the movement of the brush.
9. In receptacle cleansing apparatus, the combination with a revolvably mounted support, of a tapering plate fixed to and outstanding therefrom, a brush plate conversely tapering and slidingly engaging the first-mentioned plate, the first-mentioned plate being formed with a longitudinal recess, a bristle-carrying plate engaging the brush plate, and a bolt extending through the bristle-carrying plate and engaging the brush plate for retaining the two together, the said bolt having an extension projecting 80 into the recess of the first-mentioned tapering plate for limiting the movement of the brush plate relative thereto.
10. In receptacle cleansing apparatus, the combination with a revolvably mounted support, of a tapering plate fixed to and outstanding therefrom, a brush plate conversely tapering and slidingly engaging the first-mentioned plate, the first-mentioned plate being formed with a longitudinal recess, a bristle-carrying plate engaging the brush plate, a bolt extending through the bristle-carrying plate and engaging the brush plate for retaining the two together, the said bolt having an extension projecting 90 into the recess of the first-mentioned tapering plate for limiting the movement of the brush plate relative thereto, and a spring 95 pressing the brush plate longitudinally.
11. In receptacle cleansing apparatus, the combination with a revolvably mounted support, of a tapering plate fixed thereto and outstanding axially therefrom, a conversely tapering brush extending along and slidingly engaging said plate, means for 100 shifting the brush in one direction, and engaging means connected with the brush for being struck by the receptacle for shifting the brush in the opposite direction.
12. In receptacle cleansing apparatus, the combination with a revolvably mounted support, of a tapering plate fixed thereto and outstanding axially therefrom, a conversely tapering brush extending along and slidingly engaging said plate, means for 110 shifting the brush in one direction, engaging means connected with the brush for being struck by the receptacle for shifting the brush in the opposite direction, and means for limiting movement of the brush 120 relative to the tapering plate.
13. In receptacle cleansing apparatus, the combination with a revolvably mounted support, of a tubular tapering core fixed to and outstanding axially from the support 130

- and having radial passageways, means for supplying cleansing fluid to the bore of the core, and a brush mounted on the core and shiftable along the same for having the circles described by the active surfaces of the brush varied in diameter.
14. In receptacle cleansing apparatus, the combination with a revolvably mounted support, of a tubular tapering core fixed to and outstanding axially from the support and having radial passageways, means for supplying cleansing fluid to the bore of the core, and a brush formed of a series of separable segments shiftable along the same for having the circles described by the active surfaces of the brush varied in diameter.
15. In receptacle cleansing apparatus, the combination with a revolvably mounted support, of a tubular core fixed to and outstanding axially from the support and having its exterior surface tapering outwardly, means for supplying cleansing fluid to the bore of the core, and a brush mounted on the core and shiftable along the same for having the circles described by the active surfaces of the brush varied in diameter, the core and brush being formed with means for enabling delivery of cleansing fluid from the bore of the core to the active surfaces of the brush.
16. In receptacle cleansing apparatus, the combination with a revolvably mounted support, of a tubular core fixed to and outstanding axially from the support and having its exterior surface tapering outwardly and having radial passageways, means for supplying cleansing fluid to the bore of the core, and a brush mounted on the core and shiftable along the same for having the circles described by the active surfaces of the brush varied in diameter.
17. In receptacle cleansing apparatus, the combination with a revolvably mounted support, of a core fixed to and outstanding axially from the support, the core being tapered longitudinally and being formed of a series of segments, a series of brush segments, one for each of the core segments, the brush segments being slidably mounted on the core segments and being conversely tapered, and means for causing the brush segments to revolve with the core segments.

18. In receptacle cleansing apparatus, the combination with a revolvably mounted support, of a core fixed to and outstanding axially from the support, the core being tapered longitudinally and being formed of a series of segments, a series of brush segments, one for each of the core segments, the brush segments being slidably mounted on the core segments and being conversely tapered, means for causing the brush segments to revolve with the core segments, means for shifting the brush segments longitudinally of the core segments, engaging means for being struck by the receptacle for shifting the brush segments in the opposite direction, and means for limiting the longitudinal movement of the brush segments.

19. In receptacle cleansing apparatus, the combination with a revolvably mounted support, of a core fixed to and outstanding axially from the support, the core being tapered longitudinally and being formed of a series of segments, a series of brush segments, one for each of the core segments, the brush segments being slidably mounted on the core segments and being conversely tapered, means for causing the brush segments to revolve with the core segments, and terminal brush segments fixed to the outer ends of the main brush segments.

20. In receptacle cleansing apparatus, the combination with a revolvably mounted support, of a tubular core fixed to and outstanding axially from the support, the core being tapered longitudinally and being formed of a series of segments, a series of brush segments, one for each of the core segments, the brush segments being slidably mounted on the core segments and being conversely tapered, means for causing the brush segments to revolve with the core segments, and means for supplying cleansing fluid to the bore of the core, the edges of the segments of the core being sufficiently spaced to enable radial discharge of fluid from the bore and the edges of the segments of the brush being correspondingly spaced.

In testimony whereof I affix my signature in presence of two witnesses.

JAMES M. RUDE.
